UNITED STATES PATENT OFFICE.

WILLIAM FFORD SERVICE, OF POUGHKEEPSIE, NEW YORK, ASSIGNOR, BY MESNE ASSIGNMENTS, TO CHARLES HARDY AND CHARLES H. POTTER, BOTH OF NEW YORK, N. Y.

ROTOR FOR TIMERS.

1,334,177.

Specification of Letters Patent. Patented Mar. 16, 1920.

Application filed January 15, 1918. Serial No. 211,344.

To all whom it may concern:

Be it known that I, WILLIAM FFORD SERVICE, a citizen of the United States, and a resident of Poughkeepsie, in the county of 5 Dutchess and State of New York, have invented certain new and useful Improvements in Rotors for Timers, of which the following is a specification.

The invention relates to timers for internal combustion engines, and more particularly to the rotor member thereof which is designed to operate within a suitable casing or the like to periodically make contact with the contact members retained by or embedded in the said casing. The invention relates more particularly to a rotor member of this character embodying a pivotally mounted contact roller.

An object of the invention is to provide a 20 rotor which will be thoroughly practical and efficient and which may at the same time be manufactured at small cost.

A further object is to provide a rotor comprising a minimum of parts each of 25 which is of simple form and in which the parts may be easily and quickly assembled.

A more detailed object is to provide a rotor including a pivotally mounted member for carrying the contact roller, said member 30 being made from sheet metal bent into U-shape so as to provide spaced arms between which both the roller and the pivotal support of said member may be positioned, and in which the connecting portion of the U 35 is adapted to receive resilient pressure from a suitable spring and is also adapted to constitute an efficient stop for limiting swing ing movement of the member.

Other objects and aims of the invention, 40 more or less specific than those referred to above, will be in part obvious and in part pointed out in the course of the following description of the elements, combinations, arrangements of parts and applications of 45 principles, constituting the invention; and the scope of protection contemplated will be indicated in the appended claims.

In the accompanying drawings which are to be taken as a part of this specification, 50 and in which I have shown merely a preferred form of embodiment of the invention:—

Figure 1 is a plan of the improved rotor.

Fig. 2 is an elevation thereof; and Fig. 3 an end view.

Similar characters of reference designate corresponding parts throughout the several views.

Referring to the drawings, 10 designates a carrier member or sleeve designed to be 60 connected to a shaft of the internal combustion engine (not shown) for rotation therewith. This carrier is provided with a pair of outwardly extending ears 11 oppositely perforated near the ends to receive a pivot 65 pin or support 12 upon which is mounted, preferably outside of said ears, the arms of a U-shaped member 13, which may be held in pivotal relation to said ears by upsetting the ends of said pin. At the free ends 70 of the U-shaped member, beyond the said pivot pin 12, is journaled a contact roller 14 through which contact may be made, as is well understood. In order to hold this roller outwardly under a predetermined yielding 75 pressure sufficient to effect a proper contact, a spring 15 is coiled about the pivot pin 12, one end thereof being extended downwardly to bear against the carrier and the other end being extended backwardly to bear 80 upon the outer edge of the connecting portion of the U-shaped member 13.

The ears 11 are spaced apart a suitable distance and the spring 15 is preferably positioned between said ears so that it is effectively held against accidental dislodgment 85 at all times. The two arms of the U-shaped member 13 preferably lie against the outer flat surfaces of the ears and the connecting portion, as 16, of said U-shaped member extends across the edges of the ears in a position to engage each of the ears at the points 17 for limiting swinging movement of the U-shaped member by the spring. The points of engagement of the portion 16 with 90 the ears are thus spaced apart, one point being adjacent each of the arms of the U-shaped member so that each serves as a stop for its respective arm. At the same time the intermediate portion of the part 16 provides an 100 admirable surface to be engaged by the spring 15.

The U-shaped member, as thus described, is of very simple contour, being made from a single piece of sheet metal appropriately 105 shaped and bent. The roller 14 is mounted

between the outer end portions and then the whole is easily attached to the ears by simply telescoping the member over the ears, placing the spring, and then inserting the 5 pivot pin 12.

The connecting portion 16 is preferably formed of somewhat reduced width as compared with the width of the two arms of the U-shaped member. By this means a more 10 appropriate surface is attained for engagement by the end of the spring 15.

As many changes could be made in this construction without departing from the scope of the invention as defined in the following 15 claims, it is intended that all matter contained in the above description, or shown in the accompanying drawings, shall be interpreted as illustrative only and not in a limiting sense.

20 I claim:

1. A rotor for timers, comprising a carrier, a contact roller, a spring, and a supporting member for said roller, said supporting member being of U-shape providing 25 a pair of arms embracing both the roller and a part of the carrier and being pivotally connected both to said roller and carrier and providing also a connecting portion engaged by the spring to swing the supporting member in one direction, said connecting portion also being disposed to engage a portion of the carrier to limit swinging movement of the supporting member by 30 the spring.

2. A rotor for timers, comprising a carrier, a contact roller, a spring, and a supporting member for said roller, said supporting member being formed from a single 35

piece of sheet material bent into U-shape providing a pair of arms and a connecting portion between said arms, both the roller and a portion of the carrier being received between said arms and being pivotally connected with the arms, and said connecting portion constituting means engaged by the 40 spring for swinging the supporting member about its pivotal connection with the carrier.

3. A rotor for timers, comprising a carrier, a contact roller, the carrier having a 50 pair of ears projecting therefrom spaced apart, a supporting member for said roller, said supporting member being of U-shape providing a pair of arms embracing said roller and both of said ears, a pivot pin pivotally connecting said arms with said ears, said pivot pin traversing the space between said ears, means pivotally connecting the roller between said arms spaced from the ears, the U-shaped supporting member providing also a connecting portion extending 55 between its arms, a spring carried by said pivot pin between said ears having a portion projecting outwardly from between said ears engaging the connecting portion of the supporting member to swing the supporting member in one direction, and said connecting portion also being disposed to engage portions of each of said ears to limit swinging movement of the supporting member by 60 the spring.

Signed at New York city, in the county of New York and State of New York, this 28th day of December, A. D. 1917.

WILLIAM FFORD SERVICE.
